UNITED STATES PATENT OFFICE.

GEORGE A. BENNETT, OF MASON CITY, IOWA, ASSIGNOR TO KLIPTO LOOSE-LEAF COMPANY, OF WILMINGTON, DELAWARE, A CORPORATION OF DELAWARE.

LOOSE-LEAF BINDER.

Application filed June 29, 1923. Serial No. 648,488.

To all whom it may concern:

Be it known that I, GEORGE A. BENNETT, a subject of the King of Great Britain, and resident of Mason City, in the county of Cerro Gordo and State of Iowa, have invented new and useful Improvements in Loose-Leaf Binders, of which the following is a specification.

This invention relates to improvements in loose-leaf binders, and more particularly to extensible and contractible binders of the book-cover type for holding the sheets of "temporary" books such as loose-leaf account books.

The invention has for its principal objects to provide an extensible and contractible covering and binding means for book leaves, of simple, durable and inexpensive construction; to provide an efficient expandable loose-leaf binder which may be quickly and easily adjusted to clamp and release varying numbers of sheets or leaves; to provide improved locking means for preventing unauthorized removal of leaves from the binding means or tampering with the adjustment of the binding means; to provide means for locking the side members or hinged cover boards of an expandable book-like loose-leaf binder in closed position to prevent unauthorized persons having access to the leaves held in the binder; and to provide a holder for sheets or leaves, of neat and attractive appearance and of such construction that it may be used without injury to a desk or other support and freely handled and adjusted without liability of injury to the hands of the user.

In the accompanying drawings, Figure 1 is a view illustrating the left side face of a loose-leaf book embodying the invention, the side members of the cover being locked against opening movement;

Fig. 2 a front view of the book shown in Fig. 1;

Fig. 3 a view of the right side face of the book shown in Figs. 1 and 2;

Fig. 4 a view showing the inner side of the leaf-binding and covering means;

Fig. 5 a transverse sectional view taken on the line 5—5 of Fig. 1;

Fig. 6 a sectional view taken on the line 6—6 of Fig. 7;

Fig. 7 a sectional view taken on the line 7—7 of Fig. 6, the leaf-binding and covering means in Figs. 6 and 7 being opened out

flat as in Fig. 4 but being expanded to a greater extent than shown in Fig. 4;

Fig. 8 a detail sectional view taken on the line 8—8 of Fig. 6;

Fig. 9 a detail perspective view showing part of the leaf-binding and covering means and the locking devices therefor;

Fig. 10 a detail view showing part of one of the clamping bars and one of the hinges connecting the bar and adjacent side member or hinged board of the expandable cover;

Fig. 11 a sectional view taken on the line 11—11 of Fig. 10;

Fig. 12 a detail sectional view taken on the line 12—12 of Fig. 4;

Fig. 13 a detail sectional view through the left side member or hinged cover board of the binder, taken on the line 13—13 of Fig. 1; and

Fig. 14 a detail sectional view taken on the line 14—14 of Fig. 13, the tape clamp being shown in released position.

Referring to the drawings by numerals, 1 designates the left side member of the cover, i. e. the side member of the cover adjacent the first page of the book, 2 designates the right side member, i. e. the side member of the cover adjacent the last page of the book, and 3 designates the flexible back member of the cover which is carried by side member 1 and telescopes in the side member 2. The side members or hinged cover boards are preferably constructed as shown.

The member 1 comprises a relatively thick, rigid, rectangular plate 1^a and a relatively thin, rigid, rectangular plate 1^b arranged face to face and secured together by any suitable means such as screws, staples or glue. The plates 1^a and 1^b are preferably formed of wood, and plate 1^b covers the inner face of plate 1^a. The outer face of plate 1^a, and the top, bottom and forward edges of both plates, are covered by a sheet 1^c of flexible material (preferably leather or stout, durable fabric) which extends over the outer face of the plate and is folded inward around the top, bottom and front edges of the plates 1^a and 1^b and secured by gluing or otherwise fastening the inwardly turned edges of the sheet material to the inner face of plate 1^b. The flexible back member 3 preferably comprises an integral extension of cover sheet 1^c, as shown, said back being wide enough to telescope more or

90

95

100

105

less within member 2 in all adjusted positions of the binder. It will be obvious, however, that member 3 may consist of an independent flexible sheet secured to sheet 1^c or plate 1^a.

The side member 2 of the cover comprises the rectangular rigid plates 2^a and 2^b preferably formed of wood and rigidly secured together in the same manner as the plates of member 1, with plate 2^b covering the inner face of plate 2^a and the leather or other flexible sheet 2^c covering the outer face of plate 2^a and the top, bottom and front edges of plates 2^a and 2^b, the top, bottom and front edges of sheet 2^c being folded inward against the inner face of plate 2^b and said inturned edges being glued or otherwise secured to plate 2^b. The rear edge and main body portion of sheet 2^c are free from plate 2^b so that a pocket 4 is formed between said sheet and the plate 2^a, in which the back member 3 telescopes, the mouth of said pocket being located at the rear edge of cover side member 2.

25 A pair of rigid metal hinge plates 5 extend rearwardly from the rear edge of cover member 1, and a similar pair of metal hinge plates 6 extend rearwardly from the rear edge of cover member 2, said hinge plates 30 having their forward ends confined in slots or recesses 7 and 8, respectively, in the cover plates 1^a and 2^a and being rigidly held to said cover plates by screws 9 and 10, respectively. The slots are so located that 35 the hinge plates lie in planes midway or substantially midway between the planes of the inner and outer faces of the side members 1 and 2 of the cover with which they are connected.

40 A pair of leaf-clamping bars 11 and 12 of substantially semicircular cross-section, and preferably formed of wood, extend along the rear edges of the side members 1 and 2 of the cover inside of the back member 45 3 of the cover. Bars 11 and 12 are formed with segmental cavities 13 and 14, respectively, in their convex faces, for receiving the rear ends of the hinge plates 5 and 6, respectively. Each cavity has an inner 50 vertical wall extending parallel with the flat face of the bar from the forward edge of the bar to a point slightly more than half the width of the flat face of the bar, and a rear vertical wall extending outwardly from 55 the rear end of said inner wall to the convex face of the bar at a right angle to the flat face of the bar, so that the bars and hinge plates may swing relatively to each other through an arc of ninety degrees or slightly 60 more than ninety degrees.

The bars are pivotally held to the plates 5 and 6 by hinge straps 15 and 16 of similar construction. Each hinge strap comprises a metal strip passed through a vertical slot 65 in the rear end of the adjacent hinge plate

then doubled upon itself to form a loop or cylindrical bearing 17 embracing the post-like portion of the hinge plate located between the slot and rear edge of the plate, and the free ends of the strap are then 70 passed through a slot 18 in the bar of just sufficient width to permit passage of the two ends of the strap therethrough, and are finally bent laterally away from each other flat against the inner face of a recess 19 in the 75 flat face of the bar. The laterally bent ends of the hinge strap are covered by a metal disk 20 seated within the recess 19 flush with the flat face of the leaf-clamping bar and welded or otherwise secured to the bent 80 ends of the strap. This construction affords a stout hinge connection in which the danger of splitting of the clamping bars, or bending the hinge members, is reduced to a minimum, and in which the hinge members 85 are so constructed and attached to the bars that the outer leaves of the book will not be damaged by the hinge members or the fastening devices for said members. Owing to the cross-sectional shape of the bars and the 90 manner of connecting the bars to the cover members 1 and 2, the rear edges of the covers may be flat, i. e. lie in a plane at right angles to the faces of the covers, without interfering with relative pivotal movement 95 between the covers and bars.

The hinges being of stout construction, it is unnecessary to provide for a rolling or wiping action between the surfaces of the bars and the rear edges of the covers when 100 sheets or leaves are clamped in the binder, and to extend the binding thongs through both bars so that they may be directly and permanently secured at one end to one cover and adjustably held to the other cover, as 105 is common in many commercial forms of binders. The hinge plates are accordingly preferably made sufficiently long, a shown, to permit the rear edges of the covers to swing around the arcuate faces of the bars 110 without touching said bar faces, thus providing for free and easy swinging of the covers in opening or closing the binder. The bar 12 is formed with transverse thong-receiving grooves 24^a in its convex face in 115 line with apertures 24, so that the thongs may bend at or substantially at points in a line extending through the pivotal axis of bar 12 when the binder is closed.

The leaf-binding thongs or tapes may be 120 made of any suitable flexible material and of any suitable cross-sectional form, but preferably comprise stout leather thongs 21 of circular cross-section as shown. The thongs 21 are permanently held at one end 125 to the clamping bar 11 hinged to the left-hand cover member 1, said ends of the thongs being inserted in cylindrical cavities or recesses 22 formed at the middle or longitudinal center line of the flat face of said 130

bar. Pins 23 are driven through the bar 11 from front to rear so as to pass diametrically through the thongs and recesses 22, the ends of the pins being preferably peened or 5 headed down flush with the arcuate surface of the bar, as shown, thus eliminating projecting ends and preventing endwise movement of the pins which might damage the back member 3, injury to the hands of 10 a person using the binder, or release of the anchored ends of the thongs.

The thongs 21 extend loosely through cylindrical apertures 24 in clamping bar 12 and thence through cylindrical apertures or 15 passages 25 in the plate 2^a of cover side member 2 into a large rectangular cavity or recess 26 formed in the inner face of said plate and having its open side covered by plate 2^b. The ends of the thongs 20 which extend into cavity 26 are permanently secured to a rigid metallic connecting or anchor bar 27 by rivets 28, said bar extending substantially from top to bottom of the cavity and being loosely confined therein so 25 that the cover side member 2, together with the leaf-clamping bar 12 hinged thereto, may be shifted longitudinally of the thongs relatively to the free thong-connecting bar 27 to expand or contract the binder. In 30 order to prevent possible buckling of the flexible back member 3 when cover side 2 and bar 12 are slid along the thongs 21 toward cover side 1 and bar 11 in contracting the binder, the end of the back member 35 within pocket 4 is connected with bar 27 by two short tapes 29 which extend through slots 31 in plate 2^a connecting cavity 26 with pocket 4. The forward end of each tape 29 is rolled around bar 27 and 40 held thereto by one of the thong-attaching rivets 28, while the rear end of each tape is secured to the free end of back member 3 by rivets 30.

The cover side member 2 and the attached 45 leaf-clamping bar 12 are adapted to be held in various adjusted positions against expansion movement, i. e. against sliding movement along the thongs toward the ends of said thongs which are secured to the floating anchor bar 27, by means of a flexible tie member 32 to which said cover side member is adapted to be locked at any point 50 within the range of sliding movement of the cover side member. Said flexible member 55 preferably comprises a relatively long tape formed of stout woven fabric having its free or outer end bound by a metal tip or cap 33 and its inner end bound by a metal tip or cap 34 formed with an integral 60 hook 35 passed through a slot 36 formed in thong anchor bar 27 midway the ends of said bar. The tape 32 extends forwardly 65 through cavity 26 and the upper part of an L-shaped locking-device-receiving recess or cavity 26^a in plate 2^a located close to the

forward edge of side member 2 and forming an extension of cavity 26, and thence out through a short way or channel 26^b in said plate connecting cavity 26^a with the front edge of cover side member 2, the covering 70 2^a being provided with a slot registering with the outer end of way 26^b, the edges of said slot being preferably bound by a metal eyelet 37 having tangs 38 anchored in the top and bottom walls of way 26^b, as shown. 75 The plate 2^b is provided with a rectangular aperture the edges of which are finished with a sheet metal channel frame 39, which aperture affords access to a tape-gripping clamp and a combined latching and locking 80 device for said clamp, both mounted in cavity 26^a.

The tape gripping and locking means comprises a metal base plate 40 held to plate 2^a against the outer wall of recess 26^a by integral tangs or spurs 42 and provided adjacent its upper end with a pair of inwardly extending ears 41 lying in horizontal planes parallel with and located substantially in line with the top and bottom walls of way 26^b. The ears 41 are provided with bearing apertures receiving the trunnions 43 of the jaw 44 of the tape clamp. Jaw 44 is serrated along its outer tape-engaging edge and is formed at its inner edge with a right angle extension or broad thumb-piece 45 adapted to swing the toothed jaw forwardly and outwardly into tape-engaging position when the thumb-piece is pressed rearwardly and outwardly to a horizontal or substantially horizontal position through the opening 39 in plate 2^b. Thumb-piece 45 is formed with an integral ear 46 at its lower edge near the free end thereof, movable rearwardly and outwardly with the thumb-piece into engagement with the inner face of plate 40 to arrest the swinging movement of jaw 44 to clamping position when said jaw is at a right angle to plate 40, said ear being formed with a slot 47 into which the spring-pressed bolt 48 of a spring lock 49 is adapted to automatically snap when jaw 44 reaches its full clamping position. The end of bolt 48 and the outer edge of ear 46 are preferably beveled, as shown more clearly in Fig. 12, to permit the ear to force bolt 48 downwardly and ride past the end of the bolt as the thumb-piece is rocked to move jaw 44 to clamping position, so that the clamp may be operated to gripping position solely by pressure of the thumb of a hand gripping the front edge of cover 2, as hereinafter described. The spring-operated lock bolt 48 is adapted to be disengaged from ear 46 by the usual slidable finger-piece 50 connected with said bolt and extending through slot 51 in the casing of the lock 49 which is provided with the usual key-hole 52 for the insertion of a key 53 to operate the usual lock mechanism to positively lock 130

the spring-pressed bolt 48 in projected or locking position when it is desired to prevent release of the bolt and removal of leaves from the binder by unauthorized persons. As the lock illustrated is a well-known type of latching and locking device further showing and description thereof will be unnecessary. The casing of lock 49 is held to plate 40 below the tape-clamping 10 means by suitable fastening devices 54.

As loose-leaf binders are commonly used for holding leaves or sheets containing records of accounts or other confidential data, it is highly desirable that means be provided for sealing the binder, i. e. locking the loose-leaf book in closed condition, to prevent unauthorized persons from inspecting the contents thereof when the book is not in use. This end is accomplished in a 15 simple and effective manner by the means illustrated. As shown, tape 32 is made of sufficient length to extend (in all adjusted positions of the binder) across the front edges of the loose leaves 55 held in the 20 binder when the binder is closed, and thence into a long narrow cavity 56 formed in the inner face of plate 1^a of cover side member 1. The open face of cavity 56 is covered by plate 1^b, and covering 1^c is provided with a 25 slot registering with the forward end of the cavity or channel 56, said slot being bound by a metal eyelet 57 having tangs or prongs 58 locked in the top and bottom walls of cavity 56 in the same manner as the eyelet 37. The cavity 56 is provided with a lateral 30 lock-receiving extension 56^a along its lower edge and said cavity 56 is preferably of reduced depth from the forward edge of extension 56^a to the front edge of the cover, 35 as shown in Fig. 14.

A key-operated lock 59 of ordinary construction, having a bolt 60 movable toward and from the top of cover side member 1 by means of a key 61 adapted to be inserted in 40 the usual key-hole 62 of the lock, is housed in the extension 56^a of cavity 56 and secured to the outer face of plate 1^b by suitable fastening devices 63. The fixed member or flat metal base 64 of a binder-sealing tape-gripping clamp is rigidly held to the outer 45 face of plate 1^b by screws 65, said base extending across cavity 56 above lock 59 and being preferably countersunk in plate 1^b with its outer face flush with the outer face 50 of said plate.

The clamp base is provided with a pair of outwardly extending ears 66 substantially in line with the top and bottom walls of cavity 56, said ears having bearing apertures therein receiving the trunnions 67 of the pivoted jaw 68 of the clamp. The free edge of the jaw 68 is preferably beveled, as shown, or serrated, and is adapted to be rocked inwardly and rearwardly to a tape-gripping position at a right angle to base 55

64 by a forward and inward swinging movement of a lever 69 fixed on the lower trunnion of the jaw below the lower ear 66 and above lock 59 and movable through registering slots in covering sheet 1^c and plate 1^a 70 framed or finished by a long narrow channel frame 70 of sheet metal. One straight edge of lever 69 is adapted to abut against the outer face of plate 1^b to arrest the lever when jaw 68 is at a right angle to base 64. 75

The lever 69 is provided with a longitudinal slot 71 through which the bolt 60 of lock 59 is projected and withdrawn by key 61. The key is adapted to be inserted in the key-hole 62 of the lock through registering slots in covering 1^c and plate 1^a bound or finished by a metal channel frame 72 similar to the frame 70 and located just below said latter frame. When the binder is opened lever 69 is swung down into cavity 80 56—56^a to prevent damage to the lever or scratching of a desk or table by the lever while using the open book, the lever being frictionally held in the cavity by a spring 85 detent 73. Detent 73 comprises a strip of resilient sheet metal bent into angular form and having one end clamped between plate 1^b and the base 64 of the tape clamp, the free end of the detent 73 being forked to straddle the lower trunnion 67 between the lower ear 90 66 and lever 69 and pressing against the adjacent face of the lever.

The leaves or loose sheets 55 may be removably attached to the thongs 21 in any suitable manner. As shown, the sheets are 100 provided with circular apertures 74 near their rear edges through which the thongs extend, and are provided with narrow slots 75 extending from apertures 74 to the rear edges of the sheets. After placing the desired number of sheets or leaves upon the thongs the binder is contracted to securely hold the sheets on the thongs by clamping them together adjacent their rear edges. To contract the binder cover side member 1 is 105 placed face down with the leaves stacked upon said member, and cover side member 2 is swung upright. Tape 32 is then grasped in the right hand and side member 2 is forced downwardly edgewise with the left 110 hand until the sheets are firmly clamped between the flat faces of bars 11 and 12, whereupon thumb-piece 45 is rocked into opening 39 by pressure of the thumb of the left hand until jaw 44 of the binder-expansion-preventing clamp grips the tape and latch bolt 48 snaps through aperture 47 in ear 46 of the thumb-piece of the clamp and locks the jaw in clamping position. If it be desired 115 to prevent unauthorized persons from removing or adding leaves, the key 53 is inserted in key-hole 52 and operated to lock the bolt 48 against withdrawal by thumb-piece 50.

To seal the book against inspection when 120

not in use, it is closed and the outer end of the tape 32 is passed through eyelet 57 into cavity or channel 56 through clamp 64-68 until the tape extends substantially without 5 slack between the front edges of the cover side members 1 and 2, whereupon lever 69 is rocked inwardly through aperture 70 to cause jaw 68 of the binder-sealing clamp to grip the tape, and key 61 is inserted in key-hole 62 and operated to project bolt 60 of the lock 59 through slot 71 in the lever to prevent unauthorized releasing of clamp 64-68.

To unseal the book or free the cover side 15 members for opening movement, it is simply necessary to unlock the lock 59, whereupon a pull on tape 32 will rock the clamp member 68 to release position and simultaneously withdraw the tape from the cavity in the 20 cover side member 1. The arrangement and construction of the parts of the sealing means thus obviously permit rapid and easy unsealing when desired.

To expand the binder to add or remove 25 sheets after unsealing the binder, it is simply necessary to lay the binder face down on side member 1, open up cover member 2, insert key 53 in lock 49 to unlock the bolt 48 if it be locked, then grasp the front edge of the 30 cover member 2 between the thumb and fingers of the right hand and press down on the sheets with the left hand. Then by operating thumb-piece 50 with the thumb of the left hand to unlatch the clamp member 35 44-45, and pulling on the cover, the clamp member will automatically swing to release position and permit member 2 and bar 12 to slide along the thongs and tape away from member 1 and bar 11. It will be noted that 40 in this case also it is unnecessary to release the pivoted clamp member directly with the fingers. By using a single expansion-preventing and binder-sealing tape and the arrangement and form of clamps shown, I 45 thus provide for unsealing the binder and for expanding the binder in the shortest possible time with a minimum of effort.

What I claim is:

1. In a loose-leaf binder, the combination 50 of a side cover member, a flexible back cover member held at one side thereof to said side member, a second side cover member provided with a pocket in which said back member telescopically engages at the opposite 55 side of the back member and also having an internal cavity having an outlet through the front edge of said cover member, a pair of leaf-clamping bars pivotally held to the side cover members at the rear edges of said 60 members, a plurality of leaf-binding thongs secured at one end to the bar pivoted to the first side cover member, the second side cover member and the bar pivoted thereto having registering apertures through which 65 the thongs extend into the cavity in said

second side cover member, a thong anchor bar to which the thongs are secured at their other ends loosely confined in the cavity in said second cover member for shifting movement edgewise fore and aft of said member, a flexible tie member secured at its inner end to said anchor bar midway the ends of said bar and having its free outer end extending forwardly through the outlet of said internal cavity beyond the 70 front edge of the second cover member, and means carried by the second side cover member for locking said cover member to the tie member against movement toward the free outer end of the tie member. 75

2. In a loose-leaf binder, the combination of a side cover member, a flexible back cover member held at one side thereof to said side member, a second side cover member provided with a pocket in which said back member telescopically engages at the opposite side of the back member and also having an internal cavity having an outlet through the front edge of said cover member, a pair of leaf-clamping bars pivotally held to the side 80 cover members at the rear edges of said members, a plurality of leaf-binding thongs secured at one end to the bar pivoted to the first side cover member, the second side cover member and the bar pivoted thereto having registering apertures through which the thongs extend into the cavity in said second side cover member, a thong anchor bar to which the thongs are secured at their other ends loosely confined in the cavity in said second cover member for shifting movement edgewise fore and aft of said member, a flexible tie member secured at its inner end to said anchor bar midway the ends of said bar and having its free outer end extending forwardly through the outlet of said internal cavity beyond the front edge of the second cover member, and means carried by the second side cover member within the cavity therein for securing said cover member to the tie member against movement toward the free outer end of the tie member, 90

100 said second side cover member having an opening in its inner face affording access to said cover member securing means. 105

3. In a loose-leaf binder, the combination of a side cover member, a flexible back cover member held at one side thereof to said side member, a second side cover member provided with a pocket in which said back member telescopically engages at the opposite 110 side of the back member and also having an internal cavity having an outlet through the front edge of said cover member, a pair of leaf-clamping bars pivotally held to the side cover members at the rear edges of said members, a plurality of leaf-binding thongs secured at one end to the bar pivoted to the first side cover member, the second side cover member and the bar 115

6
pivoted thereto having registering apertures through which the thongs extend into the cavity in said second side cover member, a thong anchor bar to which the thongs are 5 secured at their other ends loosely confined in the cavity in said second cover member for shifting movement edgewise fore and aft of said member, a flexible tie member secured at its inner end to said anchor bar 10 midway the ends of said bar and having its free outer end extending forwardly through the outlet of said internal cavity beyond the front edge of the second cover member, clamping means carried by the second side 15 cover member for gripping the tie member releasable by movement of said cover member toward the free end of the tie member, and means carried by the second side cover member for positively locking the clamping 20 means against release movement.

4. In a loose-leaf binder, the combination of a side cover member, a flexible back cover member held at one side thereof to said side member, a second side cover member 25 provided with a pocket in which said back member telescopically engages at the opposite side of the back member and also having an internal cavity having an outlet through the front edge of said cover member, 30 a pair of leaf-clamping bars pivotally held to the side cover members at the rear edges of said members, a plurality of leaf-binding thongs secured at one end to the bar pivoted to the first side cover member, 35 the second side cover member and the bar pivoted thereto having registering apertures through which the thongs extend into the cavity in said second side cover member, a thong anchor bar to which the thongs are 40 secured at their other ends loosely confined in the cavity in said second cover member for shifting movement edgewise fore and aft of said member, a flexible tie member secured at its inner end to said anchor bar 45 midway the ends of said bar and having its free outer end extending forwardly through the outlet of said internal cavity beyond the front edge of the second cover member, a fixed clamp member held to the 50 second side cover member at one face of the tie member, a pivoted clamp member journaled on said fixed clamp member at the opposite face of the tie member, a lever connected to said pivoted member to rock the tie-member gripping edge thereof toward the fixed member and the front edge of the second side cover member to a gripping position at an angle to the face of said cover member, and means carried by said second 55 cover member for positively holding said lever against release movement, said clamp members and the lever holding means being housed in the cavity in the second cover member and said cover member having an 60 opening in its inner face affording access 65

to the lever-holding means and through which the lever is rocked into the cavity when actuated to move the pivoted clamp member to gripping position.

5. In a loose-leaf binder, the combination 70 of side cover members each comprising a rigid section having a covering for its outer face of flexible sheet material secured thereto around its top and bottom edges and front edge and free therefrom at its outer face and rear edge, the sheet material covering the outer face of one cover member having an integral flap extending from its rear edge and telescoping between the outer face of the rigid section of the other side 75 cover member and the inner face of the flexible cover of said latter side cover member, the rigid section of said latter side member having a cavity therein and being provided with slots extending fore and aft thereof 80 connecting said cavity with the outer face of said rigid section, a thong anchor bar shiftable in said cavity edgewise fore and aft of the cavity, a pair of leaf-clamping bars extending along the rear edges of the side cover members and pivotally held to the rigid sections thereof, the clamping bar on the cover member having the cavity being provided with transverse apertures and the rigid section of said cover member having openings in alignment with said apertures connecting the cavity with the rear edge of said section, binding thongs anchored at one end to said anchor bar and extending through said openings in the 85 rigid cover section and the apertures in the adjacent clamping bar and having their opposite ends secured to the clamping bar pivoted to the other cover member, connecting devices extending from the anchor bar 90 through the slots in the rigid section of the adjacent cover member to the free end of the flap and secured to said bar and flap, and means for holding the cover member 95 in which the anchor bar is housed against forward movement relatively to the anchor 100 bar.

6. In a loose-leaf binder, the combination 105 of side cover members each comprising a rigid section having a covering for its outer face of flexible sheet material secured thereto around its top and bottom edges and front edge and free therefrom at its outer face and rear edge, the sheet material covering the outer face of one cover member having an integral flap extending from its rear 110 edge and telescoping between the outer face of the rigid section of the other side cover member and the inner face of the flexible cover of said latter side cover member, the rigid section of said latter side member having a cavity therein and being provided with slots extending fore and aft thereof 115 connecting said cavity with the outer face of said rigid section, a thong anchor bar 120

shiftable in said cavity edgewise fore and aft of the cavity, a pair of leaf-clamping bars extending along the rear edges of the side cover members and pivotally held to the rigid sections thereof, the clamping bar on the cover member having the cavity being provided with transverse apertures and the rigid section of said cover member having openings in alignment with said apertures connecting the cavity with the rear edge of said section, binding thongs anchored at one end to said anchor bar and extending through said openings in the rigid cover section and the apertures in the adjacent clamping bar and having their opposite ends secured to the clamping bar pivoted to the other cover member, connecting devices extending from the anchor bar through the slots in the rigid section of the adjacent cover member to the free end of the flap and secured to said bar and flap, a flexible tie member secured at one end to the anchor bar midway the ends of the bar, the cover member housing the bar having an outlet from the cavity through which said tie member extends, and means in said cavity mounted on the rigid section of the cover member for gripping the tie member, the rigid section of the cover member containing the cavity having an opening in its inner face affording access to said tie member gripping means.

7. In a loose-leaf binder of the book type, the combination of a side cover member having a recess in its rear edge, a hinge plate extending fore and aft of said cover member having a vertical slot in one end and its other end extending into the recess in said member, fastening devices securing said plate to said member, a leaf-clamping bar of substantially semicircular cross-section extending along the rear edge of the cover member having a recess in its flat face and a recess in its convex face connected by a restricted passage, and a hinge strap extending through the slot in the hinge plate and doubled upon itself, the two ends of said strap passing through the restricted passage in the bar and being bent laterally outwardly away from each other in the recess at the flat face of the bar.

8. In a loose-leaf binder of the book type, the combination of a side cover member having a recess in its rear edge, a hinge plate extending fore and aft of said cover member having a vertical slot in one end and its other end extending into the recess in said member, fastening devices securing said plate to said member, a leaf-clamping bar of substantially semicircular cross-section extending along the rear edge of the cover member having a recess in its flat face and a recess in its convex face connected by a restricted passage, a hinge strap

extending through the slot in the hinge plate and doubled upon itself, the two ends of said strap passing through the restricted passage in the bar and being bent laterally outwardly away from each other in the recess at the flat face of the bar, and a metal plate welded to the laterally bent ends of the strap and seated in the recess in the flat face of the bar with its outer face flush with the flat face of the bar.

9. In a loose-leaf binder, the combination of a cover member, a clamping bar extending along the rear edge of the cover member, a plurality of parallel binding thongs secured at one end to said bar, an anchor bar to which the other ends of the thongs are connected, a second cover member slidably held to the thongs, a second clamping bar extending along the rear edge of the second cover member and provided with apertures through which the thongs loosely extend, hinges connecting each clamping bar to the adjacent cover member, a clamp carried by the second cover member, and a tie member connected at one end with the anchor bar midway the ends of the bar and extending fore and aft of the second cover member through said clamp, said clamp being manually operable to grip the tie member and releasable from gripping relation with the tie member by manual shifting of the second cover member relatively to the first cover member in a direction to separate the clamping bars.

10. In a loose-leaf binder, the combination of a cover member, a clamping bar extending along the rear edge of the cover member, a plurality of parallel binding thongs secured at one end to said bar, an anchor bar to which the other ends of the thongs are connected, a second cover member slidably held to the thongs, a second clamping bar extending along the rear edge of the second cover member and provided with apertures through which the thongs loosely extend, hinges connecting each clamping bar to the adjacent cover member, a clamp carried by the second cover member, a tie member connected at one end with the anchor bar midway the ends of the bar and extending fore and aft of the second cover member through said clamp, said clamp being manually operable to grip the tie member and releasable from gripping relation with the tie member by manual shifting of the second cover member relatively to the first cover member in a direction to separate the clamping bars, and means carried by the second cover member for positively holding the clamp against release movement.

11. In a loose-leaf binder, the combination of a cover member, a clamping bar extending along the rear edge of the cover member, a plurality of parallel binding

thongs secured at one end to said bar, an anchor bar to which the other ends of the thongs are connected, a second cover member slidably held to the thongs, a second 5 clamping bar extending along the rear edge of the second cover member and provided with apertures through which the thongs loosely extend, hinges connecting each clamping bar to the adjacent cover member, a clamp 10 a clamp carried by the second cover member, a tie member connected at one end with the anchor bar midway the ends of the bar and extending fore and aft of the second cover member through said clamp, said clamp 15 being manually operable to grip the tie member and releasable from gripping relation with the tie member by manual shifting of the second cover member relatively to the first cover member in a direction to separate the clamping bars, a clamp 20 carried by the second cover member adapted to automatically engage a part of the clamp and hold the clamp in gripping position when the 25 clamp is operated to grip the tie member.

12. In a loose-leaf binder, the combination of a cover member, a clamping bar extending along the rear edge of the cover member, a plurality of parallel binding thongs 30 secured at one end to said bar, an anchor bar to which the other ends of the thongs are connected, a second cover member slidably held to the thongs, a second clamping bar extending along the rear edge of the second cover member and provided with apertures through which the thongs loosely extend, hinges connecting each clamping bar to the adjacent cover member, a clamp carried by the second cover member, a tie member 35 connected at one end with the anchor bar midway the ends of the bar and extending fore and aft of the second cover member through said clamp, said clamp being manually operable to grip the tie member 40 and releasable from gripping relation with the tie member by manual shifting of the second cover member relatively to the first cover member in a direction to separate the clamping bars, a manually releasable latch 45 carried by the second cover member adapted to automatically engage a part of the clamp and hold the clamp in gripping position when the clamp is operated to grip the tie member, and key-operated means for locking 50 the latch in engagement with said part of the clamp.

13. In a loose-leaf binder, the combination of a cover member, a clamping bar extending along the rear edge of the cover member, a plurality of parallel binding thongs 55 secured at one end to said bar, an anchor bar to which the other ends of the thongs are connected, a second cover member slidably held to the thongs, a second clamping

bar extending along the rear edge of the second cover member and provided with apertures through which the thongs loosely extend, hinges connecting each clamping bar to the adjacent cover member, a clamp carried by the second cover member, a tie member connected at one end with the anchor bar midway the ends of the bar and extending fore and aft of the second cover member through said clamp, said clamp being manually operable to grip the tie member and releasable from gripping relation with the tie member by manual shifting of the second cover member relatively to the first cover member in a direction to separate the clamping bars, a clamp carried by the first cover member through which the free end of the tie member is adapted to be passed to hold the cover members in closed position, and key-operated locking means carried by the first cover member for locking the clamp on said member in gripping relation with the tie member, said second clamp being operable from the outer face of the first cover member to grip the tie member.

14. In a loose-leaf binder, the combination of a cover member, a clamping bar extending along the rear edge of the cover member, a plurality of parallel binding thongs secured at one end to said bar, an anchor bar to which the other ends of the thongs are connected, a second cover member slidably held to the thongs, a second clamping bar extending along the rear edge of the second cover member and provided with apertures through which the thongs loosely extend, hinges connecting each clamping bar to the adjacent cover member, a clamp carried by the second cover member, a tie member connected at one end with the anchor bar midway the ends of the bar and extending fore and aft of the second cover member through said clamp, said clamp being manually operable to grip the tie member and releasable from gripping relation with the tie member by manual shifting of the second cover member relatively to the first cover member in a direction to separate the clamping bars, a clamp carried by the first cover member through which the free end of the tie member is adapted to be passed to hold the cover members in closed position, and key-operated locking means carried by the first cover member for locking the clamp on said member in gripping relation with the tie member, said second clamp being operable from the outer face of the first cover member to grip the tie member and releasable from gripping relation with the tie member by manual shifting of the second cover member relatively to the first cover member in a direction to separate the clamping bars, a clamp carried by the first cover member through which the free end of the tie member is adapted to be passed to hold the cover members in closed position, and key-operated locking means carried by the first cover member for locking the clamp on said member in gripping relation with the tie member, said second clamp being operable from the outer face of the first cover member to grip the tie member and releasable by a pull on the tie member when freed from said key-operated locking means.

15. A loose-leaf binder of the book type comprising relatively shiftable cover mem-

bers and extensible and contractible leaf-holding means, characterized by the provision of a flexible tie member connected at one end to a part of said leaf-holding means, and means carried by each cover member for locking the cover members to said tie member

intermediate said locking means extending around the forward edges of leaves held in the binder.

10 In testimony whereof I hereunto affix my signature.

GEORGE A. BENNETT.
